(57) **CLAIM**

The ornamental design for a package for computer cable, as shown and described.

DESCRIPTION

FIG. 1 is a perspective view showing my new package design.

FIG. 2 is a top plan view thereof.

FIG. 3 is a left side elevational view thereof.

FIG. 4 is a right side elevational view thereof.

FIG. 5 is a front elevational view thereof.

FIG. 6 is a rear elevational view thereof.

FIG. 7 is a sectional view taken in the direction of the arrows along the section line 7—7 of FIG. 2.

FIG. 8 is a sectional view taken in the direction of the arrows along the section line 8—8 of FIG. 2.

FIG. 9 is a sectional view taken in the direction of the arrows along the section line 9—9 of FIG. 2; and,

FIG. 10 is a sectional view taken in the direction of the arrows along the section line 10—10 of FIG. 2.

The drawing FIGS. 3, 4, 8, 9 and 10 are drawn in an enlarged scale. The broken lines are for illustrative purposes only and forms no part of the claimed design.
